COIN HOLDER FOR A KEY CHAIN OR THE LIKE

Simon L. Friedman, 1643 N. Sayre Ave., Chicago, Ill.

Filed July 6, 1964, Ser. No. 80,700

Term of patent 3½ years

(Cl. D87—3)

FIG. 1.

FIG. 2.

FIG. 3.

FIG. 4.

FIG. 5.

FIG. 6.

FIG. 1 is a front elevational view of a coin holder for a key chain or the like showing my new design;
FIG. 2 is a side elevational view of the same;
FIG. 3 is a top plan view of the same;
FIG. 4 is a bottom plan view of the same;
FIG. 5 is an isometric view of the same on a reduced scale; and

FIG. 6 is an enlarged fragmentary cross-sectional view taken on line 6—6 of FIG. 4.

I claim:

The ornamental design for a coin holder for a key chain or the like, as shown.
